UNITED STATES PATENT OFFICE

155,379

DESIGN FOR A PAPER CUP HOLDER

Kenneth E. Bemis, Oakland, Calif.

Application March 9, 1948, Serial No. 145,001

Term of patent 14 years

(Cl. D44—9)

To all whom it may concern:

Be it known that I, Kenneth E. Bemis, a citizen of the United States, residing at Oakland, in the county of Alameda and State of California, have invented a new, original, and ornamental Design for Paper Cup Holder, of which the following is a specification, reference being had to the accompanying drawing, forming part thereof.

Fig. 1 is a top plan view of a paper cup holder, showing my new design.

Fig. 2 is a side elevation,

Fig. 3 is a bottom plan view, and

Fig. 4 is a vertical sectional view.

I claim:

The ornamental design for a paper cup holder, as shown.

KEN E. BEMIS.
